[57] CLAIM

The ornamental design of a wall mounted radio, tape player, clock and dual speaker unit, substantially as shown and described.

DESCRIPTION

FIG. 1 is a front elevational view of a wall mounted radio, tape player, clock and dual speaker unit showing my design;

FIG. 2 is a top plan view and,

FIG. 3 is a bottom plan view thereof.

FIG. 4 is a front elevational view of a modified form of the unit shown in FIG. 1.

The rear of the article is conventional.

The broken line showing of a tape cassette in FIGS. 1, 2 and 4 and, the dot-dash showing of a vertical wall panel fragment in FIG. 4 are all for "illustrative purposes only."
